ENGINE CYLINDER CONSTRUCTION

William Elmer Brill, Cleveland, Ohio, assignor to
 General Motors Corporation, Detroit, Mich., a
 corporation of Delaware

Application November 13, 1942, Serial No. 465,453

4 Claims. (Cl. 123—65)

The present invention relates generally to internal combustion engines, more especially to a cylinder liner construction for light weight, high-speed internal combustion engines.

It is well known that liquid cooled cylinder liners formed by casting are much larger in outside diameter and therefore heavier than necessary on account of foundry requirements and limitations necessary to provide cooling passages and ports of suitable dimensions therein. This increase in outside diameter and weight of the cylinder liners accordingly increases the dimensions of the engine and its weight materially.

The principal object of the present invention is to provide a light weight welded cylinder liner for a two stroke internal combustion engine in which frustum shaped scavenging and charging ports may be easily and accurately formed to provide efficient scavenging of the liner and to provide cooling passages for the liner of small radial dimensions to insure rapid axial circulation of coolant therethrough and to also reduce the overall diameter of the liners thereby reducing the dimensions and weight of the engine incorporating cylinders of this type.

The liner construction providing the above mentioned objects will be better understood by reference to the following detailed description thereof and the accompanying drawing illustrating a construction suitable for a two stroke engine having exhaust valves in the cylinder heads. It will be evident from the following that the type of liner described and illustrated may be modified to adapt it to other types of machines.

Figure 1 of the drawing is a vertical sectional view of the liner construction taken on line 1—1 of Figure 2.

Figure 2 is a transverse cross sectional view taken on line 2—2 of Figure 1.

Figure 3 is a transverse cross sectional view taken on line 3—3 of Figure 1, and,

Figure 4 is a broken away view taken on line 4—4 of Figure 3.

Referring to Figure 1, the cylinder liner assembly includes an internal sleeve 1 having an internal bore in which the engine piston, not shown, reciprocates and the external cylindrical surface of the sleeve is provided with two axially spaced lands 3 and 5 of slightly greater diameter and also cooling and stiffening fins 7 and a lower mounting flange 9 of a diameter slightly less than the lands 3 and 5. The land 3 is of sufficient axial length to allow a plurality of circumferentially spaced frustum shaped scavenging and charging air ports 11 to be easily formed

therein in a manner to be described. These ports are uncovered by movement of the piston to bottom dead center to allow scavenging and charging air to enter the sleeve 1 through these ports in conventional manner.

An upper mounting flange 13 is pressed on the upper, or head end of the sleeve 1 and this flange is provided with a downwardly extending cylindrical portion 14 having an internal diameter greater than that of the sleeve 1 adjacent thereto and an outside diameter substantially equal to that of the lands 3 and 5. A corrugated sleeve 15 serving as an upper coolant jacket is welded between the portion 14 of the upper mounting flange 13 and the upper portion of the land 3 to form a coolant space above the ports 11 and another corrugated sleeve or coolant jacket 17 is welded between the lower portion of the land 3 and the lower land 5 to form a coolant space below the ports 11. Coolant passages comprising grooves 19 extending axially across the land 3 between certain of the ports 11 serve to connect the coolant spaces either side of the ports. These passages or grooves have plates 21 of sufficient axial length and circumferential width to be welded to the land 3 either side of the grooves 19 and to the upper and lower sleeves or jackets to allow rapid circulation of the coolant axially through the above described coolant passages above, between and below the ports 11, as the radial dimension of these passages is small.

The coolant enters these passages through an inlet port 23 in the upper mounting flange 13 and passes outward through a plurality of outlet ports drilled therein, one of which is shown at 25. To insure proper controlled circulation of the coolant axially through the coolant passages a baffle plate 27, as best shown in Figures 1, 3 and 4, is welded on the inner surface of the upper mounting flange portion 13 adjacent the coolant inlet port 23. The upper portion of the baffle adjacent the port 23 is curved and the lower portion extends downward between the upper jacket 15 and sleeve 1 to a point slightly above at least one of the coolant passages 19 between adjacent ports 11.

In addition to the means described above for obtaining controlled and rapid circulation of the coolant both axially and circumferentially along the sleeve 1 and between the ports 11 which likewise enables the outside diameter of the assembly to be only slightly greater than the bore of the cylinder 1, the frustum shaped scavenging and charging ports previously mentioned are

laid out in the following manner so that they may be easily and accurately cut without distortion of the thin walled internal sleeve 1 and to also cause the air entering each of these ports to be directed toward a point A located within the sleeve 1 and displaced from the axis of the sleeve. Point A for each port 11 is located as best shown in Figure 2 at the intersection of lines a and b drawn tangent to circles of smaller diameter than the internal diameter of the sleeve A and B and concentric therewith. It will be evident that by mounting a suitable cutting tool such as a burning torch on a ball joint whose center is at point A and limiting the horizontal and vertical movement thereof by means of a fixed template of rectangular shape, the ports 11 of similar shape may be accurately formed and that the contour of the peripheral surface of these ports will be of frustum shape conforming substantially to the lines a, b, c, d, which converge inwardly toward point A as shown in Figures 1 and 2. It will be evident that the axis of each frustum shaped port is displaced with respect to the longitudinal axis of the sleeve 1. Where a burning torch is used to cut these ports no further machining of the surface is necessary and the torch may be pivoted either at point A and directed outward or fixed to a suitable pantograph which is pivoted at point A or at any point in a line extending through point A and parallel to the axis of the sleeve which enables the torch to be directed inward to cut these port openings in either the internal sleeve 1, or in both the sleeve 1 and an outer one piece sleeve or jacket which may be used in place of the multiple jacket construction described and shown. The general outline of the frustum shaped ports 11 is rectangular as shown, however, any other outline may be used as desired by substituting a template of other than rectangular shape mentioned to limit the movement of the torch about point A.

The above described method whereby frustum shaped ports 11 may be accurately formed so that the peripheral surface of each converges inwardly substantially toward a focal point A dis-

placed from the axis of the sleeve so that the scavenging air entering the cylinder sleeve through a port will be directed substantially to, or focused on point A to cause circular movement of the air within the sleeve 1. With a plurality of such ports circumferentially spaced in the cylinder sleeve 1, and exhaust valves located in the cylinder head efficient vortex or rotary end to end scavenging and charging of the cylinder sleeve will be provided.

I claim:

1. A hollow cylinder having a plurality of circumferentially spaced fluid entrance ports, said ports being of frustum shape for causing the fluid entering said ports to converge toward separate points within said cylinder, said separate points being located in a plane transverse to the cylinder axis.

2. A hollow cylinder having a plurality of circumferentially spaced frustum shaped fluid entrance ports, the axes of said ports being severally displaced with respect to the longitudinal axis of said cylinder and in the mid-plane of the ports to cause fluid entering each of said ports to converge toward a point and thereby cause rotary movement of the fluid in said cylinder about the longitudinal axis of said cylinder.

3. A hollow cylinder having a plurality of circumferentially spaced fluid entrance ports of frustum shape, the wall of each port being projected from a separate point within the cylinder and in a plane transverse to the longitudinal axis of said cylinder, each of said points being displaced from the cylinder axis to cause rotary motion of the fluid within said cylinder by entrance of fluid through said ports.

4. A hollow cylinder having a plurality of circumferentially spaced frustum shaped fluid inlet ports, the peripheral surface of each of said ports converging inwardly toward a point within the cylinder, said points being uniformly displaced from the longitudinal center line of the cylinder and in the central transverse plane of the ports.

WILLIAM ELMER BRILL.
